UNITED STATES PATENT OFFICE.

FRED A. MARCY AND GRANVILLE F. THAYER, OF PROVIDENCE, RHODE ISLAND.
ASSIGNORS TO M AND T BUTTON COMPANY, OF BOSTON, MASSACHUSETTS, A
CORPORATION OF MASSACHUSETTS.

SHOE-BUTTON.

1,261,580.

Specification of Letters Patent.

Patented Apr. 2, 1918.

Application filed December 7, 1915. Serial No. 65,615.

To all whom it may concern:

Be it known that we, FRED A. MARCY and GRANVILLE F. THAYER, citizens of the United States, residing at Providence, in the county 5 of Providence, State of Rhode Island, have invented certain new and useful Improvements in Shoe-Buttons, of which the following is a specification.

Our invention relates to ornamental buttons for shoes or other articles of apparel and consists of improvements in the method of constructing the same. The object of our invention is to provide a button having an improved form of shank or eye for attaching it to the shoe or other article, to adapt it to be more easily fed through the sewing machine, and further to provide for fastening the eye to the button in a more secure manner while allowing for greater uniformity in the shape and size of the eye.

The manner and means for carrying out our improvement are fully described in the following specification, illustrated by the accompanying drawings, in which like reference characters designate like parts. In the drawings:

Figure 1 is an enlarged sectional elevation of one form of our improved button taken in a plane extending through its vertical 80 axis;

Fig. 2, a similar view showing a slight modification in the construction of the button;

Fig. 3, a view in perspective of the metal cap or shell which covers the core of the button;

Fig. 4, a perspective view of the button-core, showing the manner of attaching the shank or eye thereto;

Fig. 5, a perspective view of the metal cap sometimes employed for finishing the under side of the button; and

Fig. 6, a perspective view of the completed button.

Referring to Figs. 1, 3 and 4, our improved button B comprises essentially a paper or fiber core C, to which is attached the shank or eye E, and a metal cap or shell S, which covers the top of the button and is formed in around its sides. Usually the core C is molded or cut from paper, fiber, cardboard or other similar material which is afterward treated and hardened in the form of a round lozenge-shaped bean. The shank or eye E

is constructed from relatively fine wire bent 55 in the form of a substantially round loop having its terminal portions crossing each other in the extensions or legs e', e', see Fig. 1. The legs e', e' are forced through the soft mass of the core C and their ends e¹, e² 60 are bent or clenched over on its top as shown more particularly in Fig. 4. After the core is treated and baked the shank E becomes firmly embedded in its structure while being secured in place by the clenched-over ends e¹, e² to prevent it from being pulled out or otherwise displaced.

Applied to the outside of the core C is the metal cap or shell S which serves to conceal the exposed ends of the shank E and also acts as a means for securing in place an outer shell or covering D of celluloid or similar material which gives the ornamental finish to the button, see Fig. 1. The cap S is struck up from thin sheet-metal in the form of a cup as shown in Fig. 3, and fits tightly around the core C with its sides bent or curled inwardly to hold it in place thereon. Usually a thin sheet of colored celluloid D is stretched or molded around the outside of the cap S to conform to the shape thereof, and its marginal edge d is folded or turned in under the rim of the cap as shown in Fig. 1. In this way the celluloid covering is held firmly in place by forcing the rim of the cap S snugly against the bottom of the core C to bind its inturned edge thereagainst. In some cases the celluloid or other colored covering for the button is applied by spraying or painting it on to 80 effect a coating which hardens in drying or is baked to set it.

In some instances the button is further ornamented or embellished by applying a polished metal center F to its top. This 95 may be constructed in the form of a relatively flat, round-headed stud having its shank f riveted through a hole s in the center of the cap S, as shown in Fig. 1, or secured to the cap in any other suitable manner.

To provide a finish for the bottom of the button a metal base or plate G is sometimes secured to its under side as illustrated in Fig. 2. The base G is preferably constructed from thin sheet-metal stamped out in saucer-like shape as shown in Fig. 5 and formed with a projecting, annular flange g on its bottom. Extending upwardly from the

flange g is a circular rim g' adapted to be driven up into the core C of the button or to be flanged outwardly under the edge of the cap S as shown in Fig. 2. With this latter arrangement the rim g' binds the edge of the celluloid against the edge of the cap S as shown at d' , Fig. 2, to secure the covering D in place. The base G is provided with a slot g^2 , see Figs. 2 and 5, through which the shank or eye E projects. As illustrated in Fig. 6 the base G provides a finish on the bottom of the button besides protecting and concealing the core C .

As before stated the essential feature of the invention resides in the form and construction of the shank or eye E and in the manner of securing it to the main part of the button.

With our present improvement the eye of the button may be constructed of much finer wire because it is anchored in the core at both ends and is therefore much more rigid and secure. The double legs e', e' of the eye serve as a reinforcement, one for the other, where they cross in entering the core C , and thus tend to stiffen and brace the whole shank. Furthermore, with our improved construction the eye is prevented from turning in the button and the double, clenched ends provide a firmer and more secure anchoring-means. A still further advantage is that the eyes may be bent up by forming dies in automatically-operated machines so that they are much cheaper to manufacture. The wire from which the eyes are constructed being of less thickness than that usually employed the buttons will feed much more freely in the raceway of the sewing-machine and as the eyes are made by

machinery they are more uniform in size, besides being more slightly in appearance. This uniformity in the size and shape of the eyes provides against their clogging in the feeding-mechanism of the sewing-machine so that hindrance to its operation is avoided and practically all waste is eliminated. It will thus be seen that our improved button is not only neater and more symmetrical in appearance but its eye can be manufactured by machinery with absolute uniformity so as to provide the economical advantages as above pointed out.

Various slight modifications might be made in the details of construction of our improved button without departing from the spirit or scope of the invention; therefore, without limiting ourselves to the exact embodiment shown and described, what we claim is:—

In an improved button for shoes or other articles of apparel, the combination with a hardened paper core, of an eye formed of relatively fine wire bent in a loop having its extremities crossing each other at the base of the core and inserted therethrough with their ends clenched over on the top thereof, a metal shell inclosing the core and extending around under its sides, and a covering of sheet-celluloid applied to the outside of the shell with its edges held under the rim thereof.

In testimony whereof we affix our signatures in presence of two witnesses.

FRED A. MARCY.

GRANVILLE F. THAYER.
